GLOVE INCORPORATING A CHANGE PURSE

Harriette Le Clair, Brockton, Mass.

Application March 15, 1946, Serial No. 654,580

3 Claims. (Cl. 2—160)

1

This invention relates to gloves in which a palm purse is incorporated.

More particularly it relates to coin purses in gloves, mittens, and the like.

Women and children often have need to carry a small sum of money, or a house key, as, money for carfare, or for an errand at a grocery. Coins for such purposes can be slipped into one's glove or into the mitten a child is wearing, but experience has shown that there is risk of the coin becoming lost, with consequences more or less serious. Therefore devices have been proposed for constructing a purse in the palm of a glove, with closure flaps and fastenings of various types. But all such hitherto known to me are unsatisfactory, because they add bulk and stiffness to the palm of the glove, and because they entail more or less discomfort to the wearer.

The purse of my invention avoids the discomfort, while attaining the safety which is requisite, because it needs no closure flap or button or slide fastener metallic fastening, such as have characterized previous palm purses. Although the pocket of my purse is in the palm of the glove, or mitten, I provide a mouth for the purse in the thumb of the glove. The edge of material at the mouth may be button-holed, or it may be faced, for suitable finish and to withstand wear. The mouth extends across the thumb or crotch; and may even be in the gusset between thumb and palm. The pocket of the purse may be the space between the surface material of the glove and its lining. If the glove has no interior lining of regular style, a patch of lining on the inner face of the palm will serve. If there is a complete lining, a course of stitches will confine coins to the palm region if that be desired. In either construction there is preferably a throat passage between the pocket and its mouth; or at least there is preferably a re-entrant angle of stitching to guard against a simple lateral movement of the hand or of the coin taking the coin directly from the pocket laterally into the mouth. The presence of the wearer's thumb tends to keep the mouth of the purse closed at all times while the glove containing the purse is being worn. Since the making of the pocket requires no more than that there be a lining, the presence of the purse causes no discomfort to the wearer.

To use the purse, the wearer poses her hand before her with thumb upward, and edges the coin into the mouth at the base of the thumb, and with gentle pressure overcomes the frictional resistance of the material of the glove as she slips the coin through this closed slit, from which

2

it falls by gravity into the pocket or body of the purse in the palm. The coin cannot escape from confinement there, without conscious effort of the wearer. She can extract the coin easily by holding her hand so that by gravity the coin falls into the part of the pocket which is toward the wrist, and then so that it falls thence into the neck that leads to the thumb. But this involves peculiar poses, in which the wearer first turns her hand upward, with wrist under the palm to let gravity settle the coin toward the wrist; and then rotates the hand to put her thumb underneath, so that the coin, in falling, falls into the neck and avoids falling back into the main body of the pocket. When the coin has been thus tossed into the neck leading to the mouth, the coin can be manipulated out through the mouth, by her other hand, overcoming the frictional resistance of the closed slit. The anatomy of the human hand is such that this sequence of hand movements and positions does not occur in the ordinary course of deorous behaviour. Hence the coin will not escape without aid of the wearer; nor without her conscious knowledge; or one may stuff the thumb into the mouth.

If the glove is removed from the hand, a folding of the thumb over into the palm, and a conventional rolling or tucking of the gloves together will prevent accidental escape of the coin.

The accompanying drawings illustrate two embodiments of the invention and also illustrate two varieties of mitten to which it is applied. It will be understood, however, that use of the invention is not limited to the particular types of mitten which are shown, and that it is equally available for gloves fabricated in any style. The presence or absence of fingers is immaterial, and the method of construction of the glove or mitten is immaterial.

In the drawings:

Figure 1 is a front view of a mitten embodying the purse of the invention, being a mitten which has no lining except the patch lining of the invention.

Figure 2 shows the main back and front blanks, and Figure 3 shows a third blank used in the making of the mitten purse of Figure 1.

Figures 4 and 5 are edge views in section respectively on the lines 4—4 and 5—5 of Figure 1.

Figure 6 is a face view of a mitten purse of the invention, in which the mitten has a lining.

Figure 7 shows a blank of material from which the mitten of Figure 6 is assumed to be made, and

Figures 8 and 9 are edge views of the mitten

and purse of Figure 6 respectively on the section lines indicated at 8—8 and 9—9 in Figure 6.

It will be understood that the drawings are diagrammatic; and that they omit to portray the soft and flexible character of the material of which the gloves and mittens will ordinarily be made. As the invention is concerned only with the palm and thumb region the specific portrayal of a mitten serves equally for a glove. But in the claims and at some places in the specification the term "glove" is used in a generic sense, to include all hand coverings, whether or not the fingers are separated from each other.

The mitten represented in Figures 1—5, made of any suitable material, is made by putting together of the three cut-outs 10, 12 and 14. They may be joined by stitching as indicated in Figures 4 and 5 to make a shape conventionally indicated in Figure 1, in any manner approved in the glove maker's art. As represented, the blank 12 is to be turned over upon the blank 10, and all edges of the two united, except at the wrist 18, and at what is to be a free edge, at the mouth 20 of the purse. Before this is done a facing 22 will have been applied to this mouth edge, and the lining patch 14, 16, will have been applied, on the part 12, as by shifting it downward and to the left from its position in the drawing, without rotating it. Then when the part 12 is turned over, the patch 14, 16 will occupy the position seen in Figure 1—having its main body between 12 and 14, but with its portion 16 projecting over and overlying the thumb part of the cut-out 10. Preferably the projecting part 16 which constitutes the front of the thumb, in the completed article as seen in Figure 1, will be of material like that of the front and back of the main parts of the mitten. However, the main body of this piece 14, which is to be a lining patch inside the mitten, may be of different and thinner material if preferred. This lining patch will ordinarily be stitched to the surface which is to be an interior surface of the front of the mitten, so that the pocket 30 will be held on the part 12 that will overlie the palm of the hand. The shape of this pocket may be varied at choice, especially the depths to which it extends toward the fingers and toward the wrist. In Figure 1 the dotted line 14 indicates the edge of the patch lining. However, the patch should preferably extend over a region, at the left of where the coin 25 is represented in Figure 1, such that while the glove is being worn the wearer can turn her hand so as to make the thumb be under the coin, so that a coin falling from the last said region will fall into the thumb instead of falling into the finger region. And there should be a depth of pocket toward the fingers, into which the coin can fall when the hand is held with fingers down, but with the thumb not under it—which will be always the ordinary down position unless the wearer by special effort gets the thumb under the coin—from which depth of finger region the coin cannot work its way by gravity to the mouth 20. This is so the coin will always be kept away from the mouth 20, however the hand may ordinarily be held or moved, except when the hand is posed so that the mouth 20 is almost directly under a wrist position of the coin. In the stitching of the patch it is preferable to emphasize the crotch between the thumb region and the palm region, as indicated at 24, where the thumb branches out from the palm, to provide additional safeguard against the coin slipping laterally from the palm pocket into the mouth. It will be observed that

the mouth is located in the thumb branch of the crotch, so that the coin cannot get to the mouth without first entering the thumb branch of the crotch.

Figures 4 and 5 show how the two pieces 10, 12 of Figure 2 go together to make the mitten, and show the pocket space 30 available for holding coins.

Figures 6—9 represent the purse in a lined mitten. In this case the only change necessary from ordinary construction of a lined glove or mitten is to cut a slit 50 through the face material of the glove, across the face of the thumb, leaving the lining intact. This slit is just outside the crotch of the thumb, and preferably will be finished as a buttonhole is finished, so as to admit a coin at that location to the space between the face material and the lining of the thumb and mitten. In that simple form the full range from wrist to finger tips, constitutes the pocket between the face material and the lining, and this, in many cases, will be satisfactory. But it is preferable that the pocket be limited in extent by a line of stitching 56 which preferably will be arranged to make a crotch 54 to prevent the coin from casually entering the thumb, as gravity moves it about while the wearer moves her hand freely and carelessly in ordinary behaviour. This keeps the coin away from the mouth except when there is the above described extraordinary pose of the hand that is wearing the mitten. In Figures 6—9 the invention is shown applied to a mitten of the style in which the cut-out for the face 42 and for the back 40 are made as one, so that the mitten is formed by folding the part 42 over upon the part 40, a lining of similar shape being applied. For Figure 8 the section is taken so as to show the entrance region, and for Figure 9 to show the body region, of the pocket 60. The lip of mouth 50 is marked 46.

Thus constructed, with complete lining or with merely a patch lining, coins can easily be put into the pocket when one's hand that is wearing the purse is held in a natural position before one; but no coin can accidentally or by gravity get to the mouth, for escape, until the hand is posed in an unnatural elevated position with the thumb down, and the palm turned sidewise outward. And meantime the location and arrangement of the purse-mouth, as an opening across the thumb in the thumb branch of the crotch, dispenses with all need for a mechanical fastener.

There is opportunity for variety in choosing the exact location and slant of the mouth, 20 or 50, and for designing the re-entrant depth of the guard stitching 24 or 54, whose function is to reduce the chances of a coin moving laterally from the pocket directly to the mouth. This guard stitching is an obstacle such that no quick lateral movement of the hand can shake the coin directly into the mouth. If the coin should be thrown merely into the passage which leads to the mouth its presence there would be felt by the wearer, and would be a warning. And, in any event, the next thoughtless movement of the hand would not be likely to be one in a direction capable of putting out the coin, by stretching the material for it to pass out through the mouth. Thus the location and arrangement of the mouth of the palm purse dispense with closure fastenings heretofore necessary, by making the chances of unnoticed escape of a small coin so small as to be negligible, and when the purse of the invention

is used for carrying a house key an unnoticed escape of the key would be practically impossible.

I claim as my invention:

1. A palm purse for a glove, mitten or the like comprising in combination the said glove; sheet material lining the inner side of the palm thereof; and stitches securing the said lining to material of the palm of the glove, so that interiorly the glove has a pocket whose opening is on that side of the pocket which is toward the thumb edge of the palm; the said pocket extending farther toward the fingers of the glove than does the said interior opening; there being an exterior opening in the surface material of the glove at the thumb edge of the palm, the way between said exterior and interior openings being aligned in the direction of the wrist; whereby a purse is constituted, whose contents the glove tends to retain while the glove is being worn, except when the hand that is wearing this glove is first pointed upward for gravity to shift the contents toward the wrist, and afterward is pointed downward, and has its thumb edge downward.

2. A palm purse for a glove, mitten or the like comprising in combination the said glove, sheet material lining the inner side of the palm thereof and extending along the thumb; and stitches securing the said lining to material of the palm so that the palm of the glove has a pocket with the opening of the pocket toward the thumb; said lining continuing beyond said opening as material of the face of the thumb of the glove; the face material of the palm having at said opening an edge constituting one lip of that opening; the said stitching having a location which extends toward the fingers and having a portion which is re-en-

trant between the said opening and that part of the pocket which is nearer the fingers, thereby to obstruct the direct lateral passing of contents of said part of the pocket to an escape at said opening.

3. A palm purse for a glove, mitten or the like comprising in combination said glove; sheet material lining the inner side of the palm thereof; and stitches securing the said lining to material of the palm, so that a pocket is in the palm of the glove; said pocket having an opening at the thumb edge of the palm; and said pocket extending further toward the fingers than does the said opening; a portion of said stitches being in a line which extends far enough toward the wrist to cover said opening against escape of contents of said part of the pocket which is nearer the fingers, by direct movement to the said opening.
